UNITED STATES PATENT OFFICE.

JAMES HIGGINS, OF THE FIFTY-NINTH REGIMENT ILLINOIS VOLUNTEERS.

IMPROVEMENT IN VENTILATING TOP-PIECE FOR TENTS.

Specification forming part of Letters Patent No. 38,583, dated May 19, 1863.

To all whom it may concern:

Be it known that I, JAMES HIGGINS, private in the Fifty-ninth Regiment of Illinois Volunteers, in camp near Jacinto, Tishomingo county, in the State of Mississippi, have invented a new and Improved Apex for Tents; and I do hereby declare that the following is a full and exact description thereof, reference being had to the accompanying drawings, and to the letters of reference marked thereon.

The nature of my invention consists of a hollow cylinder or pipe, having on its outside a double flange, the outer rims of which meet in support of each other, the inner rims being riveted or secured to the cylinder. Two or more socket-staples are riveted or secured to the outside of the cylinder, the said socket-staples being intended to receive tenons hinged onto sockets, which sockets fit onto top of the tent-poles. A hoop is to pass over the socket-staples, fitting or resting on the flanges, and to the said hoop the canvas of the tent is to be secured. The cylinders, flanges, socket-staples, tenons, and sockets for top of tent-poles, and the hoops are to be made of sheet or plate iron, or other suitable material.

To enable others to make use of my invention, I will proceed to describe its construction.

Figure 1, A. B is a cylinder or pipe of sheet-iron, or other suitable material; b b b, dotted lines connecting outlines of cylinder which are hid by the flanges; a a a, small sockets attached to cylinder. E D are conical flanges, the outer rims supporting each other, the inner rims being riveted or secured to the cylinder.

Fig. 2, C represents one of the flanges before it is fitted to the cylinder.

Fig. 3, a is one of the socket-staples for receiving tenon a', Fig. 4, to show its correspondence with a a a, Fig. 1.

Fig. 4, E is a socket for the tent-pole, having a tenon, a', hinged at c d, c d representing the hinge connecting tenon and socket,

the latter being intended to receive the upper end of the tent-poles, and the tenon fitting into socket-staples a a a, Fig. 1.

Fig. 5, F is a hoop to which the canvas of the tent is secured. The hoop passes freely over the socket-staples and fits onto the flanges, being inclined to the same angles as the flanges for that purpose.

This apex is for square, many-sided, or round tents, the pipe, when the tent is not round, conforming to the number of the sides of the tent. The pipe or cylinder acts as a ventilator in pleasant weather, and as a flue for a stove-pipe in winter. The hoop fitting well out on the flanges, will prevent the heat from injuring the canvas of the tent. The sockets being fitted to appropriate poles, and the tenons being hinged to the sockets, admit of the poles supporting the tent from the sides—either inside or out—instead of the center. By spreading the heels of the poles, the top of the tent will be lowered so that in wet weather the canvas can shrink without ripping the bottom or pulling up the pegs. By closing the heels the canvas can be stretched out smooth. By using long poles in summer the tent can be elevated to any desired height for ventilation. The tent can be set up without pegging, when the weather is not windy. When pegged down it will require more than four times the force to blow it over than if there was but one pole, the poles being at the sides and acting as braces, as well as supports.

What I claim is—

The cylinder or pipe, in combination with the flanges, socket-staples, tenons, and sockets and hoop for the support and ventilation of, and flue for stove-pipe of, tents, substantially as set forth in the specifications.

JAMES HIGGINS.
